UNITED STATES PATENT OFFICE

2,593,015

COMBUSTION BOAT AND SHIELD

George M. Dreher, Pittsburgh, Pa.

Application April 14, 1948, Serial No. 20,934

3 Claims. (Cl. 263—48)

1

My invention relates in general to combustion apparatus for use in chemical analysis and in particular to a novel combustion boat and shield for use in such apparatus, one of the chief uses of which is its employment in the determination of the carbon and sulfur content of iron or steel.

It is customary to use a boat of suitable refractory material in combustion apparatus for chemical analysis to contain the sample of material, e. g., iron or steel, of which it is desired to determine the carbon and/or sulfur content. Such boats are placed inside the usual refractory combustion tube and then the tube is placed inside a heating furnace, usually an electric furnace. The tube may be used with refractory liners between the tube and the enclosed boat, but I prefer to use a tube without a liner, but it is to be understood that my invention can be used where a tube liner is used. In any event the tube or liner soon becomes unsuitable for further use due to collections on the inner wall of the tube or liner of spatterings of iron slag from the metal samples in the combustion boat caused when the sample of iron, steel, or other material is exposed to high heat say about 2500° F., while oxygen or any other suitable gas is passed over the sample.

When the inside of the combustion tube or of the liner becomes unduly slagged so that the combustion boat cannot be properly placed in position in the tube or liner as the case may be, the affected tube or liner must be replaced, at considerable expense if the tube is used without a liner, and at lesser expense if a liner is used.

To reduce the aforesaid expense, it has been proposed to place a shield over the boat and between it and the combustion tube. Such a shield can be provided much more cheaply than even a liner, and more readily replaced. Thus both time and expense can be saved in such chemical determinations by the use of a shield over the boat.

One drawback to the use of such shields, as have been heretofore used, is the tendency of the shield to become dislodged from its proper shielding position over the boat. This is due to the explosions which commonly occur in the tube during such determinations and to jarring of the apparatus. When a shield is dislodged from shielding position its usefulness is largely impaired, as some of the spatterings will adhere to the tube which is relatively expensive, and some to the shield, so that in time both the tube and the shield must be replaced. Thus the advan-

2

tages of the known type shield are to a large degree lost.

A further drawback to the former shields which rested directly on the top of the boats was the tendency for the shields to become firmly attached to the boat with which it was used by the adherence of the slag to the top edges of the boat and the contacting surface of the shield. In such instances both boat and shield had to be discarded. My boat and shield greatly minimizes this condition.

I have observed these phenomena and have discovered how to prevent displacement of the shield and adherence of the tube and shield in the chemical determination. I have discovered a new boat and a shield having unique features which insure that the shield, even if moved upward from the boat, will return to a shielding position and fully protect the tube from spatterings, and one which is not prone to the adherence of the boat and shield.

My combustion boat has features which are new in the art, and include special side constructions which insure that the shield will always return to shielding position if dislodged, and that the shield will not rise to a location where it will not return to a proper shielding position. I do this by shaping the side walls of the boat so as to provide a seat such as a shelf-like projection around the outside wall of the boat on which the sides of the shield will rest. I also provide that the dimensions of the boat and shield are correlated with the internal dimensions of the combustion tube so that the shield cannot be lifted so far or be dislodged to such an extent as to prevent the return of a dislodged shield to a spatter shielding position. This correlation also greatly minimizes the tendency of the boat and shield to adhere.

It is an object of my invention to provide in combustion analysis apparatus, a combustion boat which has side portions which guide an anti-tilting shield to a position which will prevent spattering of the inside of the combustion tube.

It is another object of my invention to provide an anti-tilting shield having depending flanges to cover said boat, which shield cannot tilt out of shielding position.

It is a further object to provide a boat having seatings on the sides thereof to receive an anti-tilting shield having depending flanges which rest on the seatings, the proportions of the boat and shield being such as to be received in a combustion tube in such a manner that the shield

cannot be dislodged to an extent that it will not reseat itself on the boat in shielding position.

Still another object of my invention is to provide a boat and shield in which the top of the boat is normally separated from the sides of the shield, as to minimize the tendency of the boat and shield to be united by slag sputtering.

It is a still further object to provide a combustion boat and shield therefor which are simple, inexpensive, and which will enable relatively low cost determinations of the chemical contents of a desired material to be made by combustion analysis.

In the accompanying drawings, wherein I have shown presently preferred embodiments of my invention:

Figure 1 is a schematic view showing a side elevation of a heating furnace with a combustion boat and shield in operative position in the furnace;

Figure 2 is an enlarged sectional view of the combustion boat and shield therefor, in position in a combustion tube, along the line II--II of Figure 1;

Figure 3 is a longitudinal section of the boat and shield along the line III--III of Figure 2;

Figure 4 is a view similar to that shown in Figure 2, but showing a modification of the boat and shield in Figure 2;

Figure 5 is a longitudinal section of the boat and shield along the line V--V of Figure 4.

In the drawings the reference numeral 10 designates an electric combustion furnace of known construction, having a combustion chamber 11 surrounded by insulated refractory walls 12. A combustion tube 13 of any suitable refractory material passes through the side walls of the furnace, through the combustion chamber 11, and extends beyond the walls, to provide an end 14 through which a combustion boat 15 and anti-tilting shield 16 can be inserted. This end also serves as the inlet for the oxygen supply. The other end 17 of the tube may be of reduced section as shown in Figure 1 and is suitable for connection to apparatus (not shown) for determining by volumetric and other analysis, the carbon and/or sulfur content of a sample of iron or steel which may be burned in the boat 15.

In Figures 2 and 3 there is illustrated one form of combustion boat 15 and accompanying shield 16 having anti-tilting flanges. The boat which is of elongated rectangular shape consists of a base portion 17 having upstanding sides 18 and 19 and end portions 20 and 21. The sides and ends enclose a well 22. The sides 18 and 19 are each shaped as to provide steps or seats 23 and 24. A handle 25 extends from one end of the boat.

The anti-tilting shield 16, which is somewhat longer than the well enclosing sides and ends includes side flanges 26 connected by an arch portion 27. The shield is so proportioned that when in position with the flange ends on the seats 23 and 24, the sides of the flanges are spaced from the top of the upstanding sides of the boat and the arch portion is spaced from the wall of tube 13. The dimensions of the shield and boat are so related to the internal diameter of the tube that the shield 16 when dislodged by an explosion cannot rise to such an extent that the materials spattered by an explosion can pass directly beyond the flanges of the shield. After the effects of an explosion are dissipated the shield will return to a shielding position with the flange edges resting on the seats 23 and 24. Preferably the flanges

can never assume a position when confined in a tube such that the flanges of the shield can contact the top of the walls 18 and 19. However, I also contemplate a structure where the flanges and the tops of the upstanding sides of the walls may touch, or nearly so, but the proportions and shape of the structure always assure the return of the flanges to a seating position on the steps 23 and 24. It will also be observed that since the arch portion 27 is spaced above the tops of the sides 18 and 19, there will be passages between the shield 16 and the boat so as to allow free access of gases to the contents of the boats.

In Figures 4 and 5 I have shown a modification of my device, in which a boat 30 slightly different in cross section from that shown in Figures 2 and 3 is employed. The boat includes a base 31, upstanding sides 32 and 33, which slope downwardly and outwardly, and end portions 34 and 35. The sides and ends enclose a well 36. The shield which is similar to that used in the structure shown in Figures 2 and 3 bears corresponding numerals with a prime affixed to show the corresponding parts. The sloping sides 32 and 33 provide seats for the lower ends of flanges 26' of the shield 16', and the walls of the boat are so proportioned relative to each other and to the enclosing combustion tube with which the structure is designed to be used, that the shield must always return to a seating position on the side walls after a dislodgement. Nor can the shield be displaced to such extent that the spatterings may have a direct path to the tube, and preferably the flanges 26' may not contact the top portions of the walls 32 and 33.

While I have described certain presently preferred embodiments of my invention it is to be understood that changes may be made therein within the scope of the following claims.

I claim:

1. For use in a combustion analysis apparatus including a combustion tube, a combustion boat and a shield over the boat which boat and shield are received in said tube, said boat having upstanding sides, enclosing a well, a seat along said sides, said shield having depending flanges and extending from a seat on one side to a seat on the other side and having a portion which extends over and is spaced from the top of the sides of the boat, the boat and shield being so shaped as to be received in the tube and so proportioned that the flanges of the shield will not touch the top of the boat sides, nor will the bottom of the flanges extend above the top of the sides of the boat when the shield is in any operative position relative to the boat.

2. For use in a combustion analysis apparatus including a combustion tube, a combustion boat and a shield over the boat which boat and shield are received in said tube, said boat having upstanding sides and ends enclosing a well, a seat along said sides, said shield having depending flanges and extending from a seat on one side to a seat on the other side and having a portion which extends over and is spaced from the top of the sides of the boat, the boat and shield being so shaped as to be received in the tube and so proportioned that the flanges of the shield will not touch the top of the boat sides, nor will the bottom of the flanges extend over the top of the sides of the boat when the shield is in any operative position relative to the boat, the said shield being of sufficient length to extend beyond each of the well enclosing ends.

3. For use in a combustion analysis appara-

tus including a combustion tube, a combustion boat and a shield over the boat which boat and shield are received in said tube, said boat having upstanding sides, enclosing a well, said shield having spaced parallel depending flanges along its edges provided with supporting surfaces, said upstanding sides having supporting surfaces for engagement with said flange supporting surfaces to support said shield on said boat in a position forming a cover thereover and with said flanges projecting below the upper edges of said upstanding sides, said tube and said shield respectively having an inner surface and an outer surface, the latter surface being movable into contact with the former surface for preventing movement of the shield to a position in which one of said flanges is positioned above the upper edge

of one of said upstanding flanges while said boat and shield are in said tube.
